CLAIM

The ornamental design for a medical light as shown and described.

DESCRIPTION

1. Medical light
- 1.1 : Perspective
- 1.2 : Left
- 1.3 : Right
- 1.4 : Top
- 1.5 : Bottom
- 1.6 : Front
- 1.7 : Back

The figures show views of a medical light intended in particular for dental examinations; the use of a compact light source enables realization of an extremely elegant light housing with a truncated pyramid shape and low overall thickness; on both sides of the central housing there are handles which allow easy alignment and arrangement of the light. The portions of the medical light shown in broken lines form no part of the claimed design.
